UNITED STATES PATENT OFFICE.

EDWIN F. MOWER, OF BOSTON, MASSACHUSETTS, ASSIGNOR, BY MESNE ASSIGNMENTS, TO HIMSELF AND OAKLEY W. ALDEN AND DANA K. ALDEN, OF STERLING, MASSACHUSETTS.

MACHINERY FOR PRODUCING STITCH-HOLES.

SPECIFICATION forming part of Letters Patent No. 270,909, dated January 23, 1883.

Application filed November 10, 1882. (No model.)

To all whom it may concern:

Be it known that I, EDWIN F. MOWER, of Boston, in the county of Suffolk and State of Massachusetts, have invented a new and useful Improvement in Machinery for Producing Stitch-Holes in the Insoles of Boots or Shoes; and I do hereby declare the same to be described in the following specification and represented in the accompanying drawing, which 5 is a side view of such mechanism and a transverse section of an insole, showing in dotted lines the curved puncturing-awl extending through it for the purpose of forming a stitch-hole in it.

15 The nature of my invention is defined in the claim hereinafter presented.

In such drawing, A represents an awl curved near its point in manner as shown at a, it being projected from the lower end of a lever, 20 B, shaped as shown, and provided with a cylindrical fulcrum-stud, a', extended from it into a curved slot, b, made, as represented, in a stationary bracket, C. The lever at its upper end is jointed to an arm, D, to which reciprocating motions vertically are to be imparted by any suitable mechanism, in order that simi-

lar motions may be imparted to such lever. While the lever is being so moved it will not only be caused to move upward and downward, but forward and backward, so as to force the awl laterally into and through the sole in a direction to cause a stitch-hole to be formed therein through its edge and inclined therefrom to the outer surface of the sole. By properly moving the sole while the awl is out of it 30 such sole may be brought into the required positions for a series of stitch-holes to be formed in and around it, as they are usually made by a workman with an awl held in his hand. 35

I claim—

The combination of the lever, the curved awl, and the fulcrum or stud arranged with such lever, as described, with the stationary bracket having in it the curved slot to receive the said stud or fulcrum, such lever being 40 adapted to be moved upward and downward, all substantially as and for the purpose set forth.

EDWIN F. MOWER.
